UNITED STATES PATENT OFFICE.

HARRY D. JOHNSON, OF COMANCHE, OKLAHOMA.

OIL-PUMP.

1,197,939.

Specification of Letters Patent. Patented Sept. 12, 1916.

Application filed June 18, 1915. Serial No. 34,894.

To all whom it may concern:

Be it known that I, HARRY D. JOHNSON, a citizen of the United States, residing at Comanche, in the county of Stephens and State of Oklahoma, have invented new and useful Improvements in Oil-Pumps, of which the following is a specification.

This invention relates to certain new and useful improvements in pumps of the character for dispensing oils, such as gasoleme, kerosene, etc.

The object of the invention is to provide a single cylinder double-acting pump of the character described, in which provision is made for operating the pump piston on its reverse motions without the necessity of reversing the direction of motion of the operating crank.

A further object of the invention is to provide a pump of this character which is simple of construction, reliable and efficient in action, and which embodies a simple type of valved inlets and outlets and a novel construction of gearing and clutch mechanism, whereby the pump piston may be operated in opposite directions while the crank is turned continuously in one direction.

The invention consists of the features of construction, combination and arrangement of parts herein fully described and claimed, reference being had to the accompanying drawings in which:—

Figure 1 is an elevational view of the device as employed in connection with a storage receptacle, the receptacle appearing in section. Fig. 2 is a vertical section through the pump cylinder and inlet and outlet pipes on an enlarged scale. Fig. 3 is a vertical section on the line 4—4 of Fig. 1. Fig. 4 is a sectional plan view, showing the gearing. Fig. 5 is a horizontal transverse section on line 6—6 of Fig. 4, showing in full and dotted lines the clutch pins in their two working positions.

In carrying my invention into practice, I provide a pump cylinder 1 of a determined measuring capacity, say one gallon, the top and bottom heads of which cylinder are provided with stuffing boxes 2 for the passage of the upper and lower ends of the pump piston rod 3 carrying the reciprocating piston 4. The cylinder and coöperating parts of the pump are preferably arranged in practice within the storage tank or receptacle 5 containing the oil to be dispensed.

Communicating with the top and bottom

portions of the pump cylinder are intake pipes 6 and 7 provided with check valves 6' and 7', each of which opens in a direction toward the end of the cylinder with which it communicates and closes in the opposite direction against the return of the oil. Communicating with the upper and lower portions of the cylinder are also outlet pipes 8 and 9 having check valves 8' and 9' therein, each opening in a direction away from the end of the cylinder with which it communicates and closing in the opposite direction against the return of any discharged oil to the cylinder. The pipe 9 is shown in the form of a by-pass which communicates with the pipe 8 beyond the valve 8', and the pipe 8 is shown as having a continuation or prolongation which projects upwardly through the tank or reservoir and is provided with a discharge spout or nozzle 10.

The piston is adapted to be reciprocated for a continuous pumping action by means of gearing operated by a primary rotary power device and embodying means whereby the piston may be oppositely reciprocated without the necessity of reversing the direction of motion of said power device. The gearing shown for the purpose described comprises a pair of rack bars 11 and 12 arranged in parallel relation and which are integral with or suitably fixed to the upper end of the piston rod. The racked toothed surfaces of these bars are arranged in different vertical planes, and said tooth surfaces respectively mesh with gears 11' and 12' mounted upon a supporting shaft 13.

The shaft 13 is hollow and is provided with a fixed flange or collar 14 spacing the gears from each other, the gears being loosely mounted upon the said shaft 13 through which extends a concentric drive shaft 15, which is mounted to turn within the shaft 13, which latter is journaled in bearings 16 upon suitable supporting standards 17.

The hubs of the gears 11' and 12' have clutch collars 11^a and 12^a, respectively, which project beyond their relatively outer faces and are slotted or recessed to receive transverse clutch pins 11^b and 12^b, respectively, which are fixed to the driving shaft 15 and are free to move to a certain extent in slits 18 in the driven shaft 13 through which the ends of the pins project. These pins connect two shafts 13 and 15 for

rotation with each other and permit the shaft 15 to have a limited degree of sliding motion in the shaft 13, the arrangement of the pins being such that when the shaft 15 is at the limit of its sliding motion in one direction the pin 11^b will be out of engagement with the coating clutch member 11^a, while the pin 12^b will be in engagement with the clutch member 12^a, and vice versa when the shaft 15 is disposed at the limit of its opposite endwise movement. Hence it will be understood that by sliding the shaft 15 in one direction or the other either gear wheel may be clutched to the shafts for rotation therewith, while the other gear wheel may be disconnected therefrom, the arrangement of the gears and racks being such that by alternately throwing the gears into and out of action the piston may be reciprocated in opposite directions within the cylinder without changing the direction of rotation of the driving shaft 15.

Fixed to one end of the shaft 13 is a laterally extending crank arm 19, and pivoted to the adjacent end of the shaft 15, as at 20, is a driving crank 21 provided with a handle 22, which driving crank is pivotally connected with the arm 19 as indicated at 23. By this construction it will be evident that the two shafts are connected for movement in unison other than through the clutch pins and that the crank 21 when rotated will turn both shafts in unison, while communicating motion only to that gear which is at the time clutched to the shaft 13. The crank handle 21 is also pivotally movable as a lever on the connection 23 so that, through the connection 20, it may be adjusted to transmit back and forth sliding motion to the shaft 15 to alternately throw the gears into and out of clutched engagement with the driven shaft 13, as will be readily understood.

The mode of operation of the pump will be obvious from the foregoing description, assuming that one of the gears is in clutched engagement with the driven shaft and the piston is at one end of the cylinder, the rotation of the driving crank will move the piston toward the opposite end of the cylinder, thus expelling through the discharge outlet the charge of oil previously drawn into the cylinder. By now shifting the driving shaft the gear which has been in action may be thrown out of action and the other gear connected with the driven shaft, so that on the continued motion of the crank in the same direction as before the piston will be moved on its opposite or return stroke, expelling the oil previously drawn in at the opposite end of the cylinder on the expelling stroke just described. Hence a major amount of oil may be discharged on each working stroke of the piston, making the pump continuous in action, without loss

of time or inconvenience in throwing the gears into and out of action, and without the necessity of reversing the direction of motion of the driving crank, the advantages of which will be apparent.

I claim:—

1. A pump comprising a cylinder, check valved inlets and outlets communicating with the opposite ends of the cylinder, a reciprocating piston working in the cylinder, rack bars connected with the piston, a driven shaft, gears loosely mounted on said shaft, a drive shaft extending through the driven shaft, means for operating the drive shaft, clutches for connecting the gears with and disconnecting them from said shafts, and means for adjusting the drive shaft in opposite directions for alternately throwing said clutch devices into and out of action.

2. A pump comprising a cylinder, check valved inlets and outlets communicating with the opposite ends of the cylinder, a reciprocating piston working in the cylinder, rack bars connected with the piston, a driven shaft, gears loosely mounted on said shaft, a drive shaft extending through the driven shaft, means for operating the drive shaft, and means controlled by adjustments of the driving shaft for alternately connecting the gears with and disconnecting them from the shafts.

3. A pump comprising a cylinder, check valved inlets and outlets communicating with the opposite ends of the cylinder, a reciprocating piston working in the cylinder, rack bars connected with the piston, a driven shaft, gears loosely mounted on said shaft, a drive shaft extending through the driven shaft, means for driving said shaft, and clutch devices operative by reverse sliding motions of the driving shaft and for alternately connecting said gears with and disconnecting them from the shafts, whereby the piston may be reciprocated without reversing the direction of motion of the driving shaft.

4. A pump comprising a pump cylinder, check valved inlets and outlets communicating with the opposite ends of said cylinder, a reciprocating piston working in the cylinder, rack bars connected with the piston, gears meshing with the rack bars, said gears having slotted clutch members, a driven shaft on which said gears are loosely mounted, said shaft having slots, a drive shaft mounted to slide within the driven shaft, clutch pins carried by said drive shaft and projecting through said slots in the driven shaft, and means for operating the drive shaft and sliding said shaft to throw the sets of clutch members alternately into and out of action at the ends of opposite strokes of the piston.

5. A pump comprising a pump cylinder,

check valved inlets and outlets communicating with said cylinder, a reciprocating piston arranged to operate within the cylinder, rack bars carried by said piston, concentric shafts, gears loosely mounted on the outer shaft, and meshing with the rack bars, a driving crank pivotally connected with said shafts, whereby the shafts may be rotated in unison, and clutch devices operative

by the sliding movements of the inner shaft 10 for alternately connecting the gears with and disconnecting them from said shafts.

In testimony whereof I affix my signature in presence of two witnesses.
